CLAIM

The ornamental design for a control panel for a machinery operation console, as shown and described.

DESCRIPTION

FIG. 1 is a front and upper left perspective view of a control panel for a machinery operation console showing our new design;

FIG. 2 is a right side elevational view thereof, the left side elevational view thereof being a mirror image;

FIG. 3 is a top plan view thereof; and

FIG. 4 is a front elevational view thereof.

The broken line showing is included for the purpose of illustrating environmental elements only and forms no part of the claimed design.
